UNITED STATES PATENT OFFICE

SAMUEL P. BUSH, OF COLUMBUS, OHIO, ASSIGNOR TO THE BUCKEYE STEEL CASTINGS COMPANY, OF COLUMBUS, OHIO

CAR TRUCK

Application filed July 20, 1926. Serial No. 123,722.

This invention relates to car trucks and has special reference to the spring arrangement for supporting the bolster, the object being to effect equal distribution of the load 5 upon the springs. The invention is illustrated in the accompanying drawings and will be hereinafter fully set forth and defined.

In the accompanying drawings, Figure 1 is a view partly in side elevation and partly 10 in section;

Figure 2 is a view partly in plan and partly in horizontal section of a portion of a car truck embodying the present invention;

Figure 3 is a view showing the side frame 15 in transverse section and the bolster and spring plank in elevation;

Figure 4 is a view similar to Fig. 2 but showing a different arrangement of springs.

The side frame 1 is a single integral casting having an upper compression member, a lower tension member, and columns 2 connecting said members and defining an opening in which the ends of the bolster 3 and spring plank 4 are received. The columns 25 have inwardly projecting extensions 5 on their lower portions, and the spring plank rests upon and conforms to the side frame between said extensions. In the upper side of the spring plank, near the end thereof, is

30 a socket or recess 6 and over the end of the spring plank is arranged a spring bearer or carrier 7 of cruciform outline and provided at its center on its bottom with a bearing lug or rocker 8 engaging in the central portion 35 of the socket 6 whereby the spring bearer will be carried directly by the spring plank and may rock or oscillate relative thereto, the actual portions in contact between the bearer and spring plank, being in effect, point

40 bearings and adapted to provide relative rocking or oscillating movement between the two parts, rather than sliding movement as would occur where partly spherical surfaces are engageable throughout their extent of 45 surfaces. Other forms of bearings between the spring bearer and the spring plank may be used and I do not limit myself to the socket form shown. The spring bearer is provided with upstanding ribs to give it strength and

50 whereby also so the springs will be restrained

against displacement, and the arms of the bearer are disposed to extend longitudinally of the spring plank and the side frame respectively, the arms which extend along the side frame being received between the extensions of the respective columns. Upon each lobe, or each end of the arms of the spring bearer is set a spring 9 and the bolster 3 has an end inserted in the opening in the side frame to rest on the springs, the bolster end being of proper dimensions to rest upon all the 55 springs.

In Figs. 1, 2 and 3 an arrangement of four springs is illustrated, while in Fig. 4 a five-spring arrangement is shown. The spring-bearer 10 in Fig. 4 has its ends or lobes so formed as to define right angles whereas in the first-described form the lobes merge through concave arcs. The rib 11 in the form shown in Fig. 4 extends across the several ends or lobes of the spring bearer as shown at 12 to define a central rectangular box or seat for a central spring 13, there being a similar spring set on each projecting end of the bearer and the rib being extended 70 along the edges to retain the springs in place. Except in the particulars just noted, the form shown in Fig. 4 is the same as the form shown in Figs. 1, 2 and 3.

In both forms of the invention, the load 80 upon the springs is evenly distributed and the spring group is effectually held against separation while it is permitted to rock sufficiently to compensate for the vibration incident to travel or shifting of the car load.

Having fully described my invention what I claim as new and desire to secure by Letters-Patent, is:—

1. In a car truck comprising a side frame having upper and lower members, and columns, all cast integral, a bolster and spring opening between said columns, a spring plank adapted to rest upon and to fit the contour of the lower member between the columns, a spring bearer supported by the spring plank 90 over the lower member and adapted to carry springs substantially housed by the columns at their lower portion.

2. In a car truck comprising a side frame having upper and lower members, and col- 100

umns, all cast integral, a bolster and spring opening between said columns, a spring plank adapted to rest upon and to fit the contour of the lower member between the columns, and adapted to carry springs substantially housed by the columns at their lower portions.

3. In a car truck the combination of a side frame, a spring bearer mounted in the frame for rocking movement and partially housed by the columns, and bolster-supporting springs set on the bearer.

4. In a truck, the combination of a side frame, a spring plank mounted in the side frame, a spring bearer carrying bolster supporting springs and superimposed directly on the spring plank, and means whereby relative universal oscillating movement may take place between the spring plank and the spring bearer.

5. In a car truck, the combination of a side frame, a spring plank mounted in the side frame and having a spherical socket in its upper side between the sides of the side frame, and a spring bearer to carry bolster-supporting springs, said bearer being provided on its under side with a central spherically convex bearing lug seating in the socket in the spring plank.

In testimony whereof, I have signed this
specification.

SAMUEL P. BUSH.
